UNITED STATES PATENT OFFICE.

GEORG SPIESS, OF LEIPZIG, GERMANY.

SHEET-FEEDING DEVICE.

1,400,778.

Specification of Letters Patent. Patented Dec. 20, 1921.

Application filed November 10, 1920. Serial No. 423,063.

To all whom it may concern:

Be it known that I, GEORG SPIESS, a citizen of the German Republic, and residing at Leipzig, Germany, have invented certain new and useful Improvements in Sheet-Feeding Devices, of which the following is a specification.

The present invention has reference to certain new and useful improvements in automatic sheet feeding devices and relates more particularly to improvements in sheet feeding attachments of the friction wheel type for printing presses, folding machines, and the like, in which the release or lifting of the friction members from off the sheet pile is effected by the edge of the fed sheet striking an opposed feeler and causing it to co-operate with a continuously revolving drive gear, by which then, in the prior devices, a releasing mechanism of springs or weights is freed and actuated for in turn by means of a suitable motion transmitting mechanism lifting the friction feed wheels off the pile. Upon the releasing mechanism being thus freed, the parts owing to their high spring tension or weight load respectively will be actuated for disconnection very suddenly, which will cause severe strain on the parts and is apt to lead to serious damage to them. On resetting the releasing mechanism the powerful springs must be tensioned again or the weights must be lifted, as the case may be, all of which seriously interferes with the smooth operation of the machine.

According to the present invention these defects are effectively obviated by employing the movement of the lever arm carrying the feeler for positively lifting the friction wheels or rollers, as will now be fully described in connection with the accompanying drawings, in which Figure 1 is a side elevation of the improved sheet feeding attachment in the position of rest; Fig. 2 is a similar view, with the parts in the last stage of the operative movement; Fig. 3 shows a somewhat enlarged fragmentary side elevation of the feeder device in another operative position; Figs. 4, 5 and 6 represent detail parts.

Fig. 1 shows the table 1 supporting the brushed-out sheet pile 1' and the feeding friction wheel 2 let down onto the pile. The front edge of the advancing sheet encounters the finder or feeler 3, pivotally secured to the rock lever 7, pivoted at 8 and pushes it along until its upper pawl-shaped por-

tion 4 coacts with the peripheral teeth of the ratchet wheel 5 (Fig. 6). This ratchet wheel is continuously rotated in counter-clockwise direction and, obviously, will now 60 depress the pawl 4 and in so doing the latter will strike the stop pin 6 laterally extending from the double-arm rock lever 7, with the result that also this latter will be correspondingly actuated, that is to say is rocked 65 about its fulcrum pin 8. The upper end of this rock lever presents an irregular roller track composed of the relatively angularly displaced sections 9, 10, 11 and 12. In its position of rest the rock lever 7 is held in 70 the construction shown by way of example by a spring actuated lever 13 whose front roller 14 then engages in the depressed track section 12 (Fig. 1), or a rigid stop may be used for this purpose with equal effect. 75

As soon as the rock lever 7 commences to swing in clockwise direction the roller 14 will leave the track depression 12 and will eventually abruptly roll over the rounded apex 11 of the track (Fig. 2), with the result that the co-operation between the pawl 4 and the ratchet wheel 5 is somewhat eased, though not as yet completely interrupted. The spring tension of lever 13 during this operative movement is neutral as far as the 85 rock lever 7 is concerned.

Simultaneously the ascending track section 9 (Fig. 3) presses against the roller 19 of the swing lever 15, whose office it is to displace the friction wheel 2, lifts it and 90 thereby causes the shaft 16 and with it the lever arm 17 rigidly secured thereto to be rotated clockwise. The lever 17 co-operates with the one end of a bell crank 18 whose other end supports the friction wheel 2, 95 which, obviously, during the described movement will be lifted off the sheet stack (Fig. 2) so that now the feed of the sheets is discontinued. The advanced uppermost sheet is then fed through between the timedly co-operating feed rollers 20 and 21 to the printing press, folding machine, or the like, in 100 well known manner.

The friction wheel 2 is retained in the raised inoperative position as long as the 105 roller 19 remains in contact with the track section 9.

The problem now is to completely disconnect the pawl 4 from the ratchet wheel 5 without injury to the teeth and pawl respectively. In prior devices of this kind, which operated with springs or weights, the

complete disengagement between pawl and ratchet wheel was caused abruptly and before the pawl had quite reached the points of the ratchet teeth.

5 According to the present invention I use positive means for preventing the pawl 4 from skipping over and injuring the teeth of the ratchet wheel 5 in the shape of means for imparting to the rock lever 7, during 10 the disengaging operation, a speeded-up movement. Toward the end of the swing movement of the rock lever 7 the roller 14 suddenly rolls over the apex down the abruptly descending track section 10, when the 15 spring action of lever 13 will just as suddenly swing the rock lever 7 about in clockwise direction, with the result that to the pawl portion 4 of feeler 3 there is imparted a speed relatively faster than the rotary 20 speed of the ratchet wheel, so that these two members are now quickly disconnected. This disengagement is aided by a small leaf spring 22, which continuously lightly bears against the feeler 3 and which, after the 25 pawl has been lifted out of the ratchet wheel, returns the double lever 3, 4 until the pawl end 4 contacts with the pin 8. The swing motion of rock lever 7 now terminates, its nose 23 contacting with the rigid 30 stop 24.

During the stated forward feed of a sheet the shaft 25 has kept on in its counter-clockwise rotation and the entire releasing mechanism is now about to be returned into 35 the initial position and reset for a succeeding operation. The fixed cam 26, which partakes of the rotation of the shaft 25, encounters the roller 27 of the rock lever 7 (Fig. 5) and returns the latter until the roller 14 drops into the recess 12 of the roller track. Together with the rock lever the feeler 3 also is carried back into its initial position of rest. Since, in carrying back the several parts no considerable forces, such as tensioning 40 of springs or raising of weights, are to be overcome, this return movement can be accomplished in a relatively short period of time with the result that the parts are returned and reset that much quicker and the 45 time in which the feeler 3 remains in its operative position is extended, which considerably improves the performance of the machine. The lowering of the friction feed wheels 2 onto the paper stack is in no wise 50 affected by this return of the releasing mechanism.

Prior to the roller 19 leaving the track section 9 a roller 28 of the lever 15 coacts 55 with the cam 29 fixed on the shaft 25 (Fig. 4) and there is formed between the oblique track section 9 of the receding rock lever 7 and the roller 19 an interspace, the lever 15 being prevented from dropping down further. Thus, even though the releasing 60 mechanism has assumed again its position

of rest, the friction wheel 2 is still raised above the sheet pile and it will be let down only after the cam 29 has rotated far enough to oppose to the roller 28 the reduced portion 29'.

In order to prevent the edge of the fed sheet from striking the feeler 3 after the period of time in which the sheet feed must have ended has elapsed, the friction wheel 2 will be lifted by the cam 29 raising the 75 roller 28 and thus the lever 15 even if at the termination of the friction period a sheet has not advanced far enough to contact with the feeler.

What I claim is:—

1. In a sheet feeding device of the character set forth, in combination with a table supporting the stack of sheets, friction means for consecutively feeding single sheets from said stack, and a feeler in the path of the advancing sheet and operated by the impact with the front edge thereof, means actuated by said feeler for positively throwing said friction feed means out of operative contact with the sheet stack, comprising a rock lever pivotally supporting at its lower end the said feeler and presenting at its upper end an irregular roller track, a bell crank lever, a roller at the free end thereof adapted for actuation by said 95 irregular track, a second bell crank lever, said friction feed means journaled in the one end thereof and its other end coacting with the first said bell crank lever, the coöperation of said roller track and said bell crank lever roller being so timed that the friction feed means are lifted off the stack of sheets when said rock lever is operated by said feeler being tilted by the advancing sheet.

2. In a sheet feeding device of the character set forth, in combination with a table supporting the stack of sheets, friction means for consecutively feeding single sheets from said stack, and a feeler in the path of the advancing sheet, means actuated by said feeler for positively throwing said friction feed means out of operative contact with the sheet stack, comprising a rock lever pivotally supporting at its lower end the said feeler and presenting at its upper end an irregular roller track, a bell crank lever, a roller at the free end of this bell crank lever adapted for actuation by said irregular track, a member journaling 110 said friction feed means and adapted to be positively operated by said bell crank lever for throwing said friction feed means into and out of coöperation with the sheet stack in timed relation to the operation of said feeler, and means for retaining said friction feed means in the raised inoperative position for a brief period after the said rock lever has returned into its position of rest, comprising a second roller on said bell crank 115 120 125 130

lever and a continuously operable cam adapted to coact with said second roller in timed relation to the movement of said rock lever.

- 5 3. In a sheet feeding device of the character set forth, the combination with the sheet supporting table, a sheet feeding friction roller, a double-armed spring-influenced feeler in the path of the sheet feed, and
10 means positively coupling said feeler and said friction roller, of a rock lever pivotally supporting at its lower end said feeler and presenting at its upper end an irregular roller track, a continuously rotatable ratchet
15 wheel adapted to periodically coact with said feeler for actuating said rock lever, and means for quickly frictionlessly disconnecting said feeler and said ratchet wheel, com-

prising a spring-actuated roller-ended lever operating on said irregular roller track, 20 normally keeping said rock lever in the inoperative position by engaging in a depression in said track, and periodically abruptly throwing over said rock lever in clockwise direction by rolling down an abruptly descending section of said irregular roller track, for imparting to said rock lever and said feeler pivoted thereon a momentary rocking speed relatively higher than the even rotary speed of said ratchet wheel. 25
In testimony whereof I have affixed my signature in presence of two witnesses.
